CLAIM

The ornamental design for a corner shelf, as shown and described.

DESCRIPTION

FIG. 1 is a perspective view of a corner shelf showing our new design;

FIG. 2 is a top plan view thereof;

FIG. 3 is a front elevational view thereof;

FIG. 4 is a rear elevational view with the suction cups shown in phantom thereof;

FIG. 5 is a bottom plan view thereof; and,

FIG. 6 is a side elevational view of one side thereof; the other side being substantially identical.
